APPARATUS FOR AND METHODS OF
DRYING LEATHER

Joseph M. Tyndall, Columbus, Ind., and Mieth Maeser, Beverly, Mass., assignors to United Shoe Machinery Corporation, Flemington, N. J., a corporation of New Jersey

Application June 24, 1950, Serial No. 170,206

3 Claims. (Cl. 34—12)

1

This invention relates to apparatus for and a method of reducing the water content of hides and skins, and more particularly to an improved apparatus for and a method of drying leather in spread-out condition.

Tanned hides or skins, during their manufacture, must be dried at least once and perhaps several times. Heretofore, it has been the practice to stretch, spread or slack out the hides or skins individually on frames or plates preparatory to drying. Each work piece tends to shrink appreciably during drying and in order to avoid such shrinkage or loss in area of the leather, each piece is customarily either toggled to a frame or pasted to a plate as a step preparatory to drying, the toggles or paste maintaining the work piece in extended condition despite the considerable stresses set up as a result of the drying of the leather.

When glass or metal plates are used with paste as the attaching medium, excellent results are secured in that the grain surface is made smooth and highly satisfactory in so far as quality is concerned.

Unfortunately, however, the paste method, while preferred to the use of toggles, is not used for some leathers for various reasons and generally because the paste adheres to the leather after drying and must be removed by washing or buffing. Washing wets the leather again, at least to some extent, and buffing tends to damage the grain surface. It would be highly advantageous if in the use of plates, paste could be dispensed with altogether in maintaining the leather in stretched-out condition for the drying operation. One object of the invention, accordingly, is to provide a novel organization of means for effecting that result. For the purpose in view, two work confining members are provided for compressing and enclosing a leather work piece between them, the surface of one of the members being of a porous material that is vapor-transmissive when wet and the surface of the other member being impermeable to water vapor and having a smooth contacting surface for contacting the grain side of the leather. Associated with the two above-mentioned members is a heating device for driving moisture from the leather, and, in accordance with still another feature of the invention, means is provided for evacuating vapor from the leather being dried and through the porous material contacting the work.

It will be recognized that in a different aspect the invention provides a novel method of drying

2

leather in which heat is applied to the leather while it is maintained in a stretched-out condition and is confined between flat surfaces which are free of paste and with ample provision for the emission of water vapor from the leather.

5 The invention will now be more particularly described by reference to the accompanying drawing and thereafter pointed out in the claims.

The drawing illustrates one embodiment of a suitable apparatus which may be used in carrying out the present invention. It shows a main supporting plate 10 upon which two rectangular retaining frames 12 and 14 are attached by suitable fastenings such as the screws 16. Each side member of the frames 12 and 14 is made with a box-like or U-shaped cross section and these frames serve to retain a rigid porous board 20 in spaced relation to the supporting plate 10. An impermeable membrane or rubber sheet 22 is provided as a flexible covering for the porous plate 20. The sheet 22 is laid loosely over the plate 20 with a work piece 23 interposed as further described below. The edges of the sheet 22 are placed in overlapping relation with the top portion of the frame 14.

20 25 The porous plate 20 may be made of sintered ceramic material or of sintered metal the porosity of which is adequate for the purpose as will be further described. The plate 20 also may be of a laminated construction such as wire mesh or a perforated member (to lend rigidity) with felt for contacting leather to be treated. Regardless of the form of construction adopted for the plate 20 it is essential that the surface to contact the work be of such material that it is vapor-transmissive when wet.

30 35 The space between the main supporting plate 10 and the porous plate 20 is determined in extent by the frame 12 and is divided into compartments by crosspieces 30 which are notched, as at 40 32, to cause the compartments to communicate. The bottom of the enclosure (which enclosure is made up of the supporting plate 10, the frames 12 and 14, and the impermeable sheet 22) is provided with a vent 36 which leads to a vacuum pump (not shown in the drawing).

45 Means are provided for applying heat to the flexible sheet 22 and such means may take the form of infra-red lights, conventional electrical resistance units, or some other form of heater. Conveniently the heater may be and is shown in the form of a duct 40 for directing hot air over and in contact with the top surface of the sheet 22.

50 55 In carrying out the principles of the invention and operating the apparatus as disclosed, a wet

leather work piece 23 is placed between the rubber sheet 22 and the porous board 20, as shown in the drawing. Hot air is directed from the duct 40 over and in contact with the sheet 22 and simultaneous with this heating a vacuum is applied and made effective on the under side of the plate 20. This vacuum will be uniform or substantially uniform on the entire area of the porous plate 20 because of the baffle effect of the dividing strips or cross pieces 30.

Because of the vacuum, moisture and gases will be evacuated from the leather 23 and through the porous plate 20 and the leather 23 will reach the proper dry condition in a surprisingly short time. The vacuum not only expedites the emission of the water from the leather by lowering the vaporization point but it also causes the rubber sheet 22 to hold the leather 23 snugly and firmly against the plate 20 and prevent it from shrinking and losing its area as it dries.

When the leather 23 has become dried to the desired extent it may be removed with its area undiminished and with its grain surface smooth and attractive. The nature of the grain surface on the dry product is somewhat dependent upon whether that surface is placed in contact with the sheet 22 or with the surface of the board 20. It is preferred, but not essential, that the grain surface of the leather be placed against the impermeable surface and that the flesh surface be placed in contact with the porous plate 20 for in such an arrangement the grain surface is smooth and its appearance is not affected by the possible migration and localized concentration of the oils and other materials in the leather.

No paste having been used in carrying out the present invention, each work piece after being dried, may easily be removed from the apparatus and it is removed in clean condition thereby retaining the advantages of the conventional pasting method and eliminating the disadvantages thereof. It was thought that considerable difficulty would be encountered because of clogging of the pores in the porous material, particularly when the nature of wet leather is brought into consideration. Surprisingly, such difficulty has not arisen during the considerable work along this line which has been undertaken.

Having described our invention, what we claim as new and desire to secure by Letters Patent of the United States is:

1. The method of drying leather which comprises confining a spread-out wet piece of leather

between two flat surfaces, the grain side of said work piece being placed in contact with one of said surfaces which is impermeable to water vapor and the flesh side being placed in contact with the other of said surfaces which is of a porous material that is vapor-transmissive when wet, applying heat to the said piece of leather and simultaneously evacuating vapor through said porous material.

2. A leather drying apparatus, having in combination, a rigid member having a substantially plane surface on which a workpiece may be spread out, a flexible member which is relatively movable to entirely cover the spread out workpiece, one of said members being vapor-transmissive when wet and the other being impermeable to water vapor, structure sealing the vapor-transmissive member with the impermeable member to form a closed chamber when said flexible member covers the workpiece, means for heating said workpiece, and means for applying a vacuum to said chamber so that the workpiece is held in its distended condition by said flexible member as the water vapor is withdrawn through the vapor-transmissive member by the vacuum applying means.

3. The apparatus of claim 2 wherein the means for heating the workpiece comprises means for heating the impermeable member which is in contact with the workpiece.
